(57) **CLAIM**

The ornamental design for the ceiling fan housing, as shown and described.

DESCRIPTION

FIG. 1 is a side elevation view of a ceiling fan housing in accordance with my design, including the environment thereof;

FIG. 2 is an enlarged perspective view from below of the ceiling fan housing in accordance with my design, including the environment thereof;

FIG. 3 is an enlarged front elevation view of the ceiling fan housing in accordance with my design, including the environment thereof;

FIG. 4 is a reduced top plan view of the ceiling fan housing in accordance with my design, including the environment thereof; and,

FIG. 5 is a reduced bottom plan view of ceiling fan housing in accordance with my design, including the environmental thereof.

The broken lines showing environmental structure are for illustrative purposes and form no part of the claimed design. In FIGS. 2 and 3, the fan blades are shown broken away to indicate indeterminate length.

All the sides are substantially identical except for the position of the fan blades.
